UNITED STATES PATENT OFFICE.

WALTER B. KERRICK, OF LOS ANGELES, CALIFORNIA, ASSIGNOR TO KERRICK STEAM MOTORS COMPANY, OF LOS ANGELES, CALIFORNIA, A CORPORATION OF CALIFORNIA.

OIL BURNER.

Application filed March 26, 1921. Serial No. 455,930.

To all whom it may concern:

Be it known that I, WALTER B. KERRICK, a citizen of the United States, residing at Los Angeles, in the county of Los Angeles and State of California, have invented new and useful Improvements in Oil Burners, of which the following is a specification.

This invention relates to hydro-carbon burner and to a method of burning hydro-carbons; and particularly pertains to a burner of the type in which hydro-carbon fuels are vaporized in a generator by the heat of the burner and ejected from a nozzle into the mixing chamber of the burner to induce a flow of primary air to enter and mix with the vaporized fuel.

An object of this invention is to provide a method and apparatus for effecting combustion of hydro-carbon fuel by which such thorough atomization of the fuel and its intermixture with air may be effected as to permit throttling down to produce a low flame with a minimum danger of back-firing or extinguishing of the flame, and which is especially applicable for use in the generation of steam in steam driven auto vehicles to enable the operator to control the steam generation by regulation of the fuel feed.

Another object is to provide a means and method for burning hydrocarbon fuels, particularly those of the heavier variety, whereby the fuel may be vaporized, mixed with air and delivered to a burner in two separate volumes of vapors and air of different densities or proportions of mixture, and thoroughly intermixed in the combustion zone.

A further object is to provide a hydrocarbon burner for effecting the preceding object which is so constructed as to afford means of adjustment to vary the relative densities of two volumes of vapors and air to meet different conditions.

Other objects will appear hereinafter.

The invention is illustrated by the accompanying drawings, in which:

Figure 1 is a plan view of a burner adapted to carry out the purposes of the invention.

Figure 2 is a view in section as seen on the line 2—2 of Figure 1.

Figure 3 is a bottom plan view of a coni-

cal baffle by which a swirling motion is imparted to the rich mixture.

Figure 4 is an enlarged view in section as seen on the line 4—4 of Figure 2.

More specifically, 6 indicates a cylindrical burner body preferably of cast metal and formed with an outer circular wall 7 of suitable height, and an inner circular wall 8 disposed eccentric to the outer wall. The inner and outer walls are joined by a top wall 9 and a bottom wall 10, which construction provides an enclosed space 11 within the burner body, the area of the space decreasing rearwardly around the burner. The inner circular wall surrounds an opening 12 which allows atmospheric air to flow to the burner. The inner margin of the top wall 9 is formed with an inclined face 13 and the wall below this face is formed of increased thickness and is provided with a plurality of equally spaced holes 14 communicating with the space 11 to provide burner orifices for the escape of the mixture from the space 11, which mixture is designed to burn immediately above these orifices to form a plurality of flame jets around the burner. The holes 14 follow an inclined spiral path throughout their length and are of sufficient length to give a definite direction of flow to the mixture, causing the entire mixture emanating from the space 11 to take on a swirling motion and be directed upwardly and inwardly over the space 12.

The burner is provided with a horizontally disposed intake tube 15 communicating with the space 11, and flaring outwardly from the burner body to terminate at its outer end in a mouth 16. The intake tube provides a mixing chamber 17 for the admixture of vapors and air and is herein-after referred to as the lean mixture chamber. A fuel or vapor ejecting nozzle 18 is provided and positioned immediately forward of the mouth of the lean mixture chamber and is disposed directly in alignment with the center thereof to induce an equal flow of air into the mouth of the chamber at all points around the margin thereof in a manner common to Bunsen burners.

The wall 6 is formed with an opening 19 facing the intake tube 15 on a line with the

center of the latter; annular flanges 20 and 21 being formed on the opposite sides of the wall 6 on the margin of the opening 19. Mounted in the opening 19 is a tubular 5 conduit 22 which extends into the intake tube centrally thereof and terminates within the tube in spaced relation to its outer end and to the nozzle 18; the outer end of the conduit being flared as indicated at 23 to 10 facilitate entrance into the conduit of a portion of the vapors discharged from the nozzle.

The conduit 22 is adjustable longitudinally in the opening 19, so that the outer 15 end of the conduit may be spaced any suitable distance from the nozzle to meet varying conditions. Arranged in the space 12 is a discharge tube 24, one end of which engages the flange 21 and the other end portion of which is turned upwardly and terminates approximately on a plane with the burner openings 14. The conduit 22 and tube 24 constitute a passage for the heavier mixture of vapors and air whereby this 25 mixture will be discharged centrally of the air space 12 through a single orifice 25 from which a rich mixture flows when the burner is in operation.

As a means for imparting a swirling motion to the rich mixture flowing through the orifice a conical baffle 26 of larger diameter than the orifice is disposed over the orifice. The baffle is provided on its under surface with a plurality of radially disposed curved 35 vanes 27, against which the mixture impinges to be thrown off with a swirling motion, preferably in a spiral path similar to that of, and in the same direction as, the lean mixture flowing from the burner orifices 14. The baffle 26 is mounted on a stem 27 which passes downwardly in the tube 24 and is threaded for vertical adjustment 40 through a boss 28 formed on the tube, which construction permits the baffle being disposed in any desired spaced relation to the end of the discharge tube.

Surrounding the burner body is a casing 29 of a diameter greater than that of the burner body to form a passage 30 around 50 the burner body through which warm air may pass downwardly and be delivered from a point adjacent the flames to the lower portion of the opening 12. The upper portion of the casing 29 extends adjacent the top of the burner and the lower portion of the casing extends beneath the burner forming a wall 31 which is provided with air inlet openings 32 adapted to be regulated by a damper 33.

60 The burner may be employed for the combustion of gas in a fixed state, but is here shown as particularly adapted for burning liquid hydro-carbons and for this purpose is provided with a generator tube 34 disposed over the center of the burner and com-

municating with a source of hydro-carbon, not shown. The generator is here shown as comprising a single tube 35 which is fitted with an elbow 36 and connected to the nozzle. 70

The operation of the burner is as follows:

The heat of the flame, generates a vapor from liquid fuel contained in the generator, and the vapor formed which is subject to the pressure of the fuel source is ejected thereby 75 at high velocity from the nozzle into the mouth of the lean mixture chamber. The flow of vapor induces a flow of air through the mouth in a manner common to Bunsen burners and the vapor and air commingle 80 within the lean mixture chamber to form a lean combustible mixture which flows through the space 11 and through the burner orifices with a swirling motion to maintain a series of flame jets around the burner. Inasmuch as the nozzle is positioned in alignment with the mouth of the rich mixture passage, the denser portion of the vapor which tends to become confined to the center 85 of the passages, due to its inertia, does not tend to commingle readily with the air and flows directly into the rich mixture passage. From there the rich mixture flows through the orifice and is delivered with a swirling motion to the area encompassed by 90 the circular series of flame jets, which tend to retain the rich mixture within this area until it is completely consumed. When the supply of vapor is reduced practically all the vapor flows into the mouth of the rich mixture passage inducing a quantity of air with it so that the rich mixture passage and its orifice serves as a small capacity burner and the supply of fuel may be reduced to a 95 low degree without possibility of the flame 100 flashing back or becoming extinguished.

The temperature of the flame and the capacity of the burner may be regulated by the shutter valve which varies the amount of atmospheric secondary air coming to the 105 flame. The adjustable member of the rich mixture passage permits of regulating the relative amount of vapor entering the rich mixture passage.

It will be observed that the burner shown and described not only tends to prevent the escape of unburned fuel by causing the rich mixture to flow into an area surrounded by the burning lean mixture, but also serves to provide extreme flexibility and permits 110 of reducing the amount of fuel consumed to a degree only sufficient to maintain steam pressure in a boiler of an automotive vehicle when no steam is being drawn from the 115 boiler.

From the foregoing it will be seen that I have provided a means and method whereby a heavy rich mixture of vapors and air will be delivered to the central portion of the burner and discharged outwardly into a 120 125 130

series of jets of a thin mixture of vapors and air and a volume of air fed to the zone of intermixture of these mixtures to insure complete combustion of the hydrocarbon.

5 I claim:

1. In a burner, a burner body provided with a plurality of burner orifices, a rich mixture passage communicating with some of said orifices, a lean mixture passage communicating with other of said orifices, and a nozzle adapted to deliver vaporized fuel with an induced flow of air jointly to said passages whereby a rich mixture of the vaporized fuel and air enters the rich mixture passage and a lean mixture of the vaporized fuel and air enters the lean mixture passage.

2. In a burner, a burner body provided with a plurality of burner orifices, a tube connecting with some of the orifices, another tube of smaller diameter disposed within the first tube and communicating with other of the orifices, each of said tubes formed with a mouth open to the atmosphere and concentric with each other, and a nozzle disposed opposite the concentric mouths to deliver fuel to each.

3. In a burner, a burner body provided with a plurality of burner orifices, a rich mixture passage communicating with some of said orifices, a lean mixture passage communicating with other of said orifices, a nozzle adapted to deliver vaporized fuel jointly to said passages whereby a portion of the vaporized fuel enters the rich mixture passage and a portion of the vaporized fuel enters the lean mixture passage and induces a flow of air therewith, and means for imparting a swirling motion to a mixture issuing from all of said orifices.

4. In a burner, a burner body provided with a plurality of burner orifices, a tube connecting with some of the orifices, another tube of smaller diameter disposed within the first tube and communicating with other of the orifices, each of said tubes formed with a mouth open to the atmosphere and concentric with each other, a nozzle disposed opposite the concentric mouths to deliver fuel to each, and means on said burner body for imparting a swirling motion to a mixture issuing from all the orifices.

5. In a burner, a burner body having a plurality of burner orifices and formed with an opening disposed in the center of said body, a tube communicating with said orifices adapted to conduct a mixture of vaporized fuel and air to said orifices and formed with a mouth communicating with the atmosphere, another tube disposed within said first named tube formed with a mouth communicating with the interior of the first named tube and terminating at its

other end in an orifice disposed centrally in 65 said opening, and a nozzle adapted to eject fuel into the mouth of said first named tube.

6. In a burner, a burner body having a plurality of burner orifices and formed with an opening disposed in the center of said 70 body, a tube communicating with said orifices adapted to conduct a mixture of vaporized fuel and air to said orifices and formed with a mouth communicating with the atmosphere, another tube disposed within said 75 first named tube formed with a mouth communicating with the interior of the first named tube and terminating at its other end in an orifice disposed centrally in said opening, a nozzle adapted to eject vaporized 80 fuel into the mouth of said first named tube, and adjustable means disposed over the last named orifice to impart a swirling motion to mixture issuing therefrom.

7. In a burner, a burner body having a 85 plurality of burner orifices and formed with an opening disposed in the center of said body, a tube communicating with said orifices adapted to conduct a mixture of vaporized fuel and air to said orifices and 90 formed with a mouth communicating with the atmosphere, another tube disposed within said first named tube formed with a mouth communicating with the interior of the first named tube and terminating at its 95 other end in an orifice disposed centrally in said opening, a nozzle adapted to eject vaporized fuel into the mouth of said first named tube, adjustable means disposed over the last named orifice to impart a swirling 100 motion to a mixture issuing therefrom, and a vapor generator disposed over said burner body and communicating with said nozzle.

8. In a burner, a burner body having a 105 plurality of burner orifices and formed with an opening disposed in the center of said body, a tube communicating with said orifices adapted to conduct a mixture of vaporized fuel and air to said orifices and 110 formed with a mouth communicating with the atmosphere, another tube disposed within said first named tube formed with a mouth communicating with the interior of the first named tube and terminating at its other end in an orifice disposed centrally in 115 said opening, a nozzle adapted to eject fuel into the mouth of said first named tube, and a casing surrounding said burner body and adapted to convey heated air to the lower end of the opening in said burner body. 120

9. In a burner, a burner body having a plurality of burner orifices and formed with an opening disposed in the center of said body, a tube communicating with said orifices adapted to conduct a mixture of vaporized fuel and air to said orifices and 125 formed with a mouth communicating with the atmosphere, another tube disposed with-

in said first named tube formed with a mouth communicating with the interior of the first named tube and terminating at its other end in an orifice disposed centrally in said opening, a nozzle adapted to eject vaporized fuel into the mouth of said first named tube, adjustable means disposed over the last named orifice to impart a swirling motion to mixture issuing therefrom, and a 10 casing surrounding said burner body and

adapted to convey heated air to the lower end of the opening in said burner body.

10. The method of combusting hydrocarbon fuel consisting in injecting a rich mixture of vaporized fuel and air into a relatively thin mixture of vaporized fuel and air, imparting a swirling motion to the two mixtures in a combustion zone, and igniting the commingled mixtures. 15

WALTER B. KERRICK.
